ANTENNA FOR A RADIO OR TELEVISION SET

Donald William Peterson, Maple Shade, N.J., assignor to
RCA Corporation

Filed May 27, 1970, Ser. No. 23,164

Term of patent 14 years

Int. Cl. D14—03, 99

U.S. Cl. D26—14

Fig. 1.

Fig. 2.

Fig. 3.

Fig. 4.

FIG. 1 is a perspective view of an antenna for a radio or television set showing my new design, the broken lines shown for illustrative purposes only and forming no part of the claimed design;

FIG. 2 is a right side elevation thereof,

FIG. 3 is a front view elevation thereof; and

FIG. 4 is a top view thereof.

I claim:

The ornamental design for an antenna for a radio or television set, as shown and described.
